SPRING RIGGING FOR LOCOMOTIVES AND
OTHER VEHICLESHarry A. Hoke, Altoona, Pa., assignor to The
Pennsylvania Railroad Company, Philadelphia,
Pa., a corporation of Pennsylvania

Application August 7, 1937, Serial No. 157,828

5 Claims. (Cl. 267—54)

My invention relates generally to spring rigging for locomotives and other vehicles. More particularly, my invention relates to the manner of connecting the spring hanger to the spring and to the equalizer. This invention is a modification of the broad idea disclosed in an application for United States Letters Patent filed by me June 25, 1937, Serial No. 150,275, and the present application is a continuation in part as to all subject-matter common to these two applications.

For some years the spring rigging in use on railway locomotives has included a spring hanger connected at its ends to an equalizer and to the spring by means of gibs. These gibs engaged the hanger through slots formed in the hanger. Trouble was experienced from excessive wear between the gibs and these slots. This wear resulted in a very loose fit allowing the gibs to incline from the vertical. This causes an excessive load and a spreading strain on the hangers at the slots. Eventual failure of the hangers in a relatively short time was the shortcoming of this rigging.

Therefore, the principal object of my invention is to provide a gib which will overcome this excessive wear and strain at the weakened points of the hanger. Another object of my invention is to provide a gib which will freely operate with guided vertical movement. Another object of my invention is to reduce the wear and tear and spreading strain on the slots in the hanger by providing a separate guide to engage the hanger at a point removed from the point of engagement between the gib proper and its slot. Still further advantages of my invention will become apparent from the following detail description of an embodiment of my invention, reference being had to the accompanying drawing.

Fig. I of the drawing is a side elevation of part of a conventional locomotive truck partially broken away to better disclose important details of my invention.

Fig. II is a sectional view taken about the lines II—II of Fig. I.

Fig. III is a fragmentary side elevation partly in section of the spring and hanger connection.

Fig. IV is a perspective view showing the gib in place in the hanger.

Fig. V is a perspective view of the gib.

In Fig. I there is shown a conventional locomotive truck having a frame 1, wheels 2, journal boxes 3, center plate 4, center pin 5, equalizers 6, spring hangers 7, semi-elliptical springs 8 and gibs 9 and 10.

My invention is specifically concerned with the gib 9 which connects the upper parts of the hanger 7 to the semi-elliptical spring 8 through which the hanger 7 extends, and with the gib 10 which connects the lower part of the hanger 7 with the equalizer 6. Of course my invention could be used in other types of trucks than the one shown in Fig. I. Gibs 9 and 10 are alike and the following description of gib 9 also applies to gib 10. The gib 9 engages a slot 14 in the hanger 7 in the usual way. The cross section of the gib 9 is shaped according to the slot 14 in the hanger 7. The bottom engaging edge of the gib 9 is rounded as at 16 and is of sufficient length to properly engage the spring 8 in a cooperating groove and distribute the pressure as shown. The upper edge 17 of the gib 9 is also rounded but is much shorter than the edge 16, and cooperates with the upper portion of the slot 14 of the hanger 7, its length being governed by the thickness of the hanger 7. Shoulders 18 and 19 are provided at each end of the rounded edge 17, and spaced according to the width of the hanger 7 which fits between the shoulders 18 and 19.

Having described the conventional gib from which my invention has been developed, it is clear that with the conventional gib any wear at all between the slot 14, and the gib 9, the gib 9 will incline from the vertical and exert a gradually increasing spreading strain on the hanger 7 from within the slot 14. My improved form of gib is further provided with a guiding element 24 formed integrally with each of the gibs 9 and 10, and this guiding element 24 overcomes the above mentioned objectional tendency in the unguided or unsupported form of gib. This element 24 has a rectangular cross-section and extends downward from the gib 9 and upward from the gib 10, thus always extending toward the center of the hanger 7. A guide slot 25 is formed in the hanger in continuation of each slot 14 and the elements 24 are designed to lie snugly in the slot 25 with capacity for free sliding movement. It should be noted that the total length of the gib 9 or 10 and its guiding element 24 is sufficiently less than that of the two slots 14 and 25 to allow a substantial longitudinal movement of the gib 9 or 10 in relation to the hanger 7. This construction allows for free vertical movement of the gib 9, maintains the gib in a vertical position at all times, and also prevents excessive pressure on the sides of the slot 14, in the spring hanger 7, through which the gib 9 passes.

This guiding element 24 thus distributes the guiding strain to a point in the hanger removed

from the weak point at the slot 14, thereby relieving the wear in the slot 14 and avoiding any spreading strain within the slot 14. It is obvious that the length of the element 24 and the distance between the slot 14 and the slot 25 greatly reduce the effective spreading strain according to the principles governing the operation of levers.

The operation of my invention is obvious from the above description and comments. In this manner, I provide a simple means for avoiding the rapid deterioration of the hangers of a spring rigging without in the slightest amount reducing the free play at the connections. The gib of my invention always remains vertical in its free vertical movement and the life of the spring rigging so equipped has been considerably increased. The design is such that the center line of the gib is kept substantially in line with the center line of the hanger and no increase in space is required for the hanger and gib.

While I have described a preferred embodiment and certain modifications of my invention above in some detail, it will be obvious to one skilled in the art that further variations and changes can be made without departing from the spirit of the invention as hereinafter claimed.

Having thus described my invention, I claim:

1. In a spring rigging having a spring hanger, a gib connectingly engaging said hanger and another element of said rigging, said gib extending through an opening in said hanger provided for that purpose, a guide slot formed in said hanger

in continuation of said opening, a guiding element attached to said gib and operating in said guide slot.

2. The invention of claim 1 wherein the exposed side surfaces of said guiding element are substantially flush with the corresponding and associated surfaces of said spring hanger.

3. In a spring rigging having a spring connected to another element by a spring hanger, said hanger extending through said spring and said other element, gibs extending through said hanger at each end for contacting said spring and said other element, said gibs having guiding elements attached thereto and operating in slots in said hanger, said guiding elements with associated slots extending into the openings in said spring and other element.

4. In a spring rigging having a spring hanger projecting through another element of said rigging and being connected thereto by a gib projecting through said hanger, a guiding element formed integrally with said gib, a guide slot formed in said hanger in continuation of the opening receiving said gib, said guiding element sliding easily in said guide slot, and shoulders on said gib to receive said hanger therebetween.

5. The invention of claim 4 wherein the guiding element is of a thickness which is equal to that of the hanger whereby the guiding element does not project beyond the side surfaces of the hanger.

HARRY A. HOKE.
